UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,452, dated November 21, 1882.
Application filed August 11, 1882. Term of patent 31 years.

To all whom it may concern:

Be it known that I, JULIUS PEGEL, of New York, in the State of New York, have invented a new and original Design for Carpets, of which 5 the following is a specification.

This invention relates to a new and original design for carpets and similar fabrics; and it consists in the novel grouping and configuration of figures, hereinafter more fully described.

10 The accompanying photograph illustrates a face view of a carpet having my new design.

The blank field *a* fills the open spaces between the flower groups. The blank field *b* underlies for the most part the flower groups 15 and juts out over the field *a* in many irregular coral or lichen-like projections, following many of the projecting sprays of the flower groups themselves.

20 A is a leaf and flower cluster, with large open roses at its center, clusters of star-shaped flowers on the left, and two pendent bunches of small flowers on the right, with leaf sprays projecting on all sides.

25 B is a smaller cluster with open roses and scattered star-shaped flowers and leaves.

C is a small leaf cluster, with a spray of small flowers below.

D is a cluster, having two large open flowers and some star-shaped flowers at the center and surrounding leaf and bud clusters.

E is a large leaf and flower group, with large open flowers centrally, groups of star-shaped flowers and leaves to the left, and a group of small flowers with long flag-like leaves on the right, with projecting sprays on all sides.

30 I claim—

1. The design for carpets, consisting of the fields *a* and *b*, substantially as shown.

2. The design for carpets, consisting of the groups A, B, C, D, and E, substantially as 35 shown.

3. The design for carpets, consisting of the groups A, B, C, D, and E and the fields *a* and *b*, substantially as shown and described.

JULIUS PEGEL.
